Patented Sept. 14, 1915.

UNITED STATES PATENT OFFICE.

ADOLPH W. GAST, OF CHICAGO, ILLINOIS.

LETTER-BOX.

1,133,548.

Specification of Letters Patent. Patented Sept. 14, 1915.

Application filed November 23, 1912. Serial No. 733,067.

To all whom it may concern:

Be it known that I, ADOLPH W. GAST, a citizen of the United States, and a resident of Chicago, in the county of Cook and State of Illinois, have invented certain new and useful Improvements in Letter-Boxes; and I do hereby declare that the following is a full, clear, and exact description thereof, reference being had to the accompanying drawings, and to the letters of reference marked thereon, which form a part of this specification.

This invention relates to improvements in letter boxes more particularly intended for use in entrance-halls of apartment buildings and consists of the matters hereinafter described and more particularly pointed out in the appended claim.

In the drawings: Figure 1 is a view representing a front elevation of my improved letter-box. Fig. 2 is a view representing a vertical section through the same in a plane indicated by the line 2—2 of Fig. 1. Fig. 3 is a view representing a partial horizontal section through the box in a plane indicated by the line 3—3 of Fig. 1. Fig. 4 is a perspective view of one of the name-plates used in connection with my improved letter-box.

The improved box is intended to be arranged with others of like construction in a row attached to the side wall of the entry-way of an apartment building, with one box for each apartment. As illustrated herein, two boxes are provided as in the case of a two apartment building, or in a four apartment building where two letter-boxes are arranged on one side of the entry-way and two more on the opposite side thereof.

The improved box is preferably made of sheet metal with a front-plate of heavier metal and the main body of the box is intended to be let into the wall while the front plate, overlapping the sides and ends of the box, is secured against the outer surface of said wall.

The improved box consists of a shell 10, comprising a horizontal top wall 11, a back wall 12 and side walls 13 and also, as shown, a downwardly and forwardly inclined false bottom wall 14, the purpose of which will presently appear. Adjacent boxes are divided by means of a partition wall 13^a where more than one box is used in a row. Each box has a bottom wall 22, which is hinged at its rear margin to the back wall 12 of the box and has locking engagement at its

front margin with the front wall plate 16. When said bottom wall 22 is unlocked, it falls down to rest upon the inclined false bottom wall 14 and acts as a chute to deliver the mail from the box.

16 indicates the front plate which forms the front wall of the box. Said plate 16 has in front of each box a letter-drop opening 17: a name-plate opening 18 above the letter-drop, said opening being covered by a transparent or translucent plate 25 on which appears the name of the tenant of the apartment corresponding to the letter-box; a bottom opening 19 located in front of the inclined false bottom wall 14 through which the mail is adapted to fall when the box is opened; and an opening 20 above the name-plate in line with which is arranged a tube 21 that forms part of the familiar call-tube 75 leading to the apartment. Said plate is also provided with a larger opening 17^a which is closed by means of a glass plate 17^b through which the contents of the box may be viewed. The letter-drop opening 17 is 80 normally closed by the usual hinged flap 24.

A paper compartment 23 is provided at the side of each box, the same preferably extending the full length of the box from the top to the bottom thereof and the full depth 85 from front to rear wall. Said paper compartment is divided from the main body of the box by means of a partition wall 23^a and a slot 23^b is formed in the front plate through which the papers may be inserted 90 into the compartment 23. As will be understood the papers are folded flat when inserted into this compartment and may or may not protrude therefrom. This provides a place for the papers which now, in boxes 95 at present used, usually have to be placed on a ledge or on the floor in the neighborhood of the letter-boxes, with the result that as the papers are not identified with the apartment to which they are addressed, they are frequently lost or are not received by the proper parties. The call-tube 21 is mounted in the box in any convenient manner and is provided, as usual, near its front end with a conical enlargement 21^a in order 100 to direct the sound waves from the voice into the tube.

The name-plate 25 is frosted on its rear face so as to receive and retain a negative stamped or painted impression of the name 110 of the tenant. By thus placing the name on the rear of the glass plate it is protected

from erasure or disfigurement. The said plate is attached to the front plate 16 by means making it removable from the front of the box so that when required the name 5 may be erased and a new one substituted. As shown, a rabbet 26 is provided about the name-plate opening to form a seat for the name-plate and the same is held in place by means of an open frame 27 which engages 10 its margins and which is secured to the outer face of the front plate by suitable screws.

There is provided within each box an electric lamp bulb 28. Said lamp, as shown, is 15 mounted on an arm 29 fixed to the rear face of the front plate above the letter-drop opening and intermediate the sides of the box. Said lamp is electrically connected in a familiar manner to a source of electric 20 current (not shown) which may either be a battery or the main electric system of the building. The lights of the several boxes of a row of boxes are all arranged on the same circuit, and a switch 30 of any familiar 25 construction is placed on the front plate of the box, and is arranged to throw on the current for all the lamps at once. The lamps throw the light not only on the name-plate but also illuminate the interior of the 30 boxes. When the switch 30 is turned, one looking for a person in the apartment building, may read at a glance the illuminated names of all those on the boxes or, if it is his own box, may see whether there is any 35 mail in the box.

The usual call-buttons 31 for the call-bells are placed on the bottom of the front wall of the box, but the electric circuits controlled by these buttons are preferably connected to a different source of electric sup- 40

ply from that of the illuminating lamps, so as to prevent the batteries of one system from being worn out on the other system.

I claim as my invention:—

A letter box comprising vertically adjacent compartments, a plate forming the front wall of said compartments, said plate being provided with vertically alined name plate openings, letter-drop openings and window openings, there being an alined set 45 of said openings associated with each compartment, transparent plates covering said window openings, said name plate openings each having a plate receiving seat, translucent plate adapted to rest on each of said seats with its front face flush with the face of the front wall plate, an open frame removably securing each of said name plates to said front wall plate, each name plate being provided on its rear face with a contrasting imprint of the name, a bracket plate, fixed to the back face of the front wall plate, there being one of such bracket plates located in each compartment above the name plate opening, an electric lamp 50 supported in each bracket and adapted to illuminate the interior of each of said compartments and also the rear face of each name plate and a switch in circuit with said lamps fixed to the front wall plate and operable from the outside of said box for controlling said lamps.

In testimony, that I, claim the foregoing as my invention I affix my signature in the presence of two witnesses, this 20th day of November A. D. 1912.

ADOLPH W. GAST.
